UNITED STATES PATENT OFFICE.

ARTHUR F. PYM, OF CLIFTON, MASSACHUSETTS, ASSIGNOR TO UNITED SHOE MACHINERY CORPORATION, OF PATERSON, NEW JERSEY, A CORPORATION OF NEW JERSEY.

UPPER-SHAPING MACHINE.

Application filed June 15, 1922. Serial No. 568,446.

This invention relates to machines for use in the manufacture of boots and shoes for shaping the upper materials; and is herein illustrated in its application to a well-known 5 type of bed lasting machine, and more particularly as applied to means for shaping the toe portion of the upper materials. It will be recognized, however, that in many of its aspects the invention is not limited to a machine of the type shown nor restricted in its 10 applicability to the shaping of the toe end portion of the upper.

In machines which include in their organization means for effecting relative movement between the upper shaping or lasting mechanism and the shoe heightwise of the shoe, for example to accomplish what is usually termed the upwiping of the upper, it is important to terminate such relative movement at the point where the wipers and the shoe are in proper relation for the overwiping operation, in order that the upper may be wiped inwardly over the bottom of the shoe in the most effective manner and also 25 in order that the wipers may not lose effective control of the upper between the upwiping and overwiping operations, as they are likely to do if the upwiping operation is carried too far. In the well-known commercial 30 type of bed lasting machine the operator presses the wipers inwardly about the toe by the use of the usual hand lever while he operates the treadle to move the wipers heightwise of the toe, and in determining when to 35 stop the upwiping operation he is governed principally by the decrease of resistance encountered when the wipers pass above the edge of the shoe bottom. In the use of such an organization the tendency is to raise the 40 wipers too far with consequent danger of losing to some extent the control of the upper, and the best results in lasting require the exercise of considerable care in order to avoid such consequences.

45 The present invention, in one important aspect, provides a novel construction and arrangement of means for limiting the above-described relative movement between upper shaping or lasting means and the shoe in the 50 direction of the height of the shoe. In the construction shown the limit of upwiping movement of the wipers is determined for each shoe by relative adjustment of parts of the wiper-operating mechanism under control of a device which is positioned by en-

gagement with the bottom of the shoe. More particularly, for the purposes in view, the relatively adjustable parts of the operating mechanism in the construction herein illustrated comprise a lever having a constant limit of movement and the effective length of which is determined by the action of the shoe engaging means. Insurance is thus afforded that for each particular shoe the upwiping operation will be terminated at the proper point and the wipers will be positioned in the most effective relation to the shoe for the overwiping operation without any loss of control of the upper materials.

55 A further feature of the invention consists in novel means for varying the limit of relative movement of lasting means and the shoe in proportion to relative adjustment between such means and the shoe. The machine herein shown, as usual in machines of the type 60 illustrated, includes means for adjusting the wipers relatively to the shoe by tilting them about an axis extending laterally of the shoe, and for purposes of the invention a connection is provided between the wiper 65 adjusting means and the means for determining by engagement with the bottom of the shoe the limit of upwiping movement of the wipers, as a further means of control to compensate for adjustment of the wipers.

70 Another feature of the invention consists in novel means for effecting in succession a relative movement of the shoe and the lasting means or wipers for upwiping the upper and a relative movement in the reverse direction for compressing the margin of the upper on the bottom of the shoe. These operations are facilitated in the construction 75 shown by the provision of mechanism which reverses its movement automatically in response to continued movement in the same direction of the treadle or equivalent operating device whereby the wipers are raised to wipe the upper upwardly about the toe. The particular construction shown comprises 80 a toggle which is straightened by movement of the treadle to raise the wipers to their upper limit of movement determined as hereinbefore described and which is thereafter broken by further movement of the treadle 85 in the same direction to move the wipers downwardly to compress the margin of the upper. A novel feature of the invention also 90 consists in means for signaling the operator at the point where the relative movement of 95 the wipers is terminated.

the lasting means and the shoe is reversed to indicate that the overwiping operation should be performed, such means in the construction herein shown comprising a device 5 which becomes operative to oppose yielding resistance to continued movement of the treadle at that point in its movement when the toggle is in straightened condition.

Still another feature consists in novel 10 means for preventing undue drag of the wipers on the upper materials as they are retracted from over the shoe, the illustrative embodiment of this feature comprising a device which acts automatically on the reverse 15 movement of the treadle to lengthen the toggle by which downward compressing movement is imparted to the wipers, thereby raising the wipers during their return movement to a position higher than that which they 20 occupy at the beginning of their compressing movement.

In a further important aspect, a novel feature of the invention consists in the provision of means for facilitating correct relative adjustment between a shoe and means for operating on the shoe, this feature of the invention being illustrated herein in its relation to angular adjustment of the end-embracing wipers to position them in substantially parallel relation to the plane of that portion of the shoe bottom upon which they are to operate. Machines of the type illustrated include adjusting devices which are utilized to tip the wipers lengthwise and laterally of the shoe, and heretofore such adjustments have been made without any definite assurance as to when the wipers are properly positioned for the most effective action on the shoe.

40 For purposes of this invention the machine herein shown has mechanism which is associated with and controlled by the wiper-adjusting means for indicating visually to the operator the angular position of the wipers. While the proper position which the wipers should assume for the most effective results may be determined in different ways, the machine herein shown is further provided, as an important feature, with 45 means for measuring the inclination of the shoe bottom. More particularly, the constructions shown comprises a hold-down having members for engaging the bottom of the shoe at different locations and mechanism 50 operated by relative movement of said members to indicate to the operator the inclination of the shoe bottom both lengthwise and laterally of the shoe. By observing the measured inclination of the shoe bottom, and 55 by correspondingly adjusting the wipers as determined by their indicating mechanism, the operator is thus enabled quickly and accurately to set the wipers in accordance with the requirements of the shoe.

60 Still another important feature of the in-

vention consists in novel wiper operating and controlling means having particularly in view the correct conformity of the wipers to the shoe and effective pressure of the wipers on all parts of the shoe which they engage. For the purposes in view, the construction shown comprises a novel organization including compensating mechanism whereby the wipers adjust themselves to the toe with relative pressures automatically proportioned as between the end and the sides of the toe, and also as between the opposite sides of the toe, in response to the resistance which they encounter, and which may be substantially equalized at all points about the end of the shoe. This construction is particularly useful in a machine of the type herein shown wherein the wipers are utilized to wipe the upper heightwise of the shoe, since they adjust themselves to the different contours of the shoe at different levels while maintaining an effective wiping pressure at the sides of the toe as well as at the end of the toe. For the purpose of preventing premature closing of the wipers, the construction shown also includes means for preventing such closing movement until the wipers have been advanced substantially to the end of the toe, including also provision for shifting movement of the wipers toward the right or the left upon their engagement with the shoe. Since it is desirable on some kinds of work that in the overwiping operation the wipers receive advancing and closing movements in fixed proportion to each other, the invention further provides means for preventing compensating action of the wipers as they are advanced and closed in the overwiping of the upper. To facilitate these different operations of the wipers 105 mechanism is provided for locking or releasing different parts of the operating connections as required at different times in the operative movements of the wipers. For operating and controlling the wipers in the 110 manner described, the construction shown comprises various relatively movable parts, including a system of relatively movable racks and pinions, and features of the invention are also to be recognized in different 115 combinations and relations of these parts.

The above and other features of the invention, including also various combinations and details not hereinabove particularly set forth, will now be described with reference 120 to the accompanying drawings and pointed out in the claims.

In the drawings:

Fig. 1 is a side elevation of so much of a bed lasting machine as is necessary to illustrate my invention;

Fig. 2 is a side elevation of part of an alternative form of head-lifting mechanism;

Fig. 3 is a sectional view showing my improved holdown device arranged for indi- 130

cating the transverse and longitudinal inclinations of the shoe bottom;

Fig. 4 is a section on the line 4—4 of Fig. 3, showing the scale for indicating transverse inclination;

Fig. 5 is a section on the line 5—5 of Fig. 3, showing the means for measuring transverse inclination;

Fig. 6 is a section on the line 6—6 of Fig. 3, showing the scale for indicating longitudinal inclination;

Fig. 7 is a top plan view of the compensating wiper mechanism, with the cover plate removed;

Fig. 8 is a top plan view of the toe-lasting head;

Fig. 9 is a detail view of part of the operating lever and its handle;

Fig. 10 is an end elevation, looking from the left in Fig. 1, showing the lower part of the machine;

Fig. 11 is a section on the line 11—11 of Fig. 8, showing the mechanism for indicating the inclination of the toe-lasting head;

Fig. 12 is a side elevation looking in the direction of the arrows 12—12 in Fig. 8, and showing part of the mechanism for operating the novel compensating wipers;

Fig. 13 is a section on the line 13—13 of Fig. 8, showing the construction of the wiper head; and

Fig. 14 is a section on the line 14—14 of Fig. 13, showing the relation of certain parts of the wiper head.

The above-described drawings illustrate one form of my invention as embodied in a machine of the type known as a bed lasting machine. A machine of this type is shown in United States Letters Patent No. 1,018,477, granted Feb. 27, 1912, on application of Matthias Brock, and reference may be made to that patent for a more complete description of parts not hereinafter fully discussed.

The illustrated machine comprises generally a suitable frame 20, a heel support 22, a toe support 24, devices indicated at 26 for lasting the heel end of a shoe, and devices to be further described for operating on the toe end of the shoe. Power may be delivered to the machine for jacking the shoe by means of a belt engaging pulley 28 (Fig. 10), which operates through a cyclic clutch 50 to turn a crank 30 (Fig. 1), which in turn operates the main cam shaft through pawl-and-ratchet connections as described in United States Letters Patent No. 1,373,482, granted April 5, 1921, on application of Matthias Brock.

The toe-lasting devices are carried by a head 40, arranged to be tilted about spindle 42 by manipulation of handle 44, the spindle 42 being mounted in bearings in an upper slide 45 which is mounted to be shift-

ed angularly with respect to a laterally-movable slide 46 by the use of hand wheel 50, slide 46 being arranged to be moved automatically widthwise of the shoe during the up-wiping movement of the lasting head, as shown in United States Letters Patent No. 1,390,755, granted Sept. 13, 1921, on application of Matthias Brock. Slide 48, which supports slide 46, is longitudinally movable under the control of handwheel 49 on a vertically movable slide 52 arranged to be raised and lowered by a link 54. These various parts may be, and are illustrated as being, similar to the corresponding parts shown in the above-identified Letters Patent.

As has been explained, the raising and lowering of slide 52 is arranged to be controlled by means, illustrated as comprising a hold-down 60 engaging the shoe, which acts as a feeler controlled by the shoe to vary the effective action of a treadle 62 in such a manner that the wiper members are raised to a predetermined height with respect to the height of the shoe bottom, whereupon further movement of treadle 62 in the same direction after or during the inward movement of the wipers, moves slide 52 in the opposite direction to apply heavy pressure to the wiped-over upper materials of the shoe.

The hold-down is mounted on a sliding rod 64, and is lowered in the customary manner by a link 66 connected to treadle 68. A bracket 70 is securely clamped on rod 64, and on this bracket is formed a supporting face which is formed with an undercut groove slidingly to receive a rack block 74. The bottom projecting portion of bracket 70 has a threaded hole for a threaded adjusting bolt 72 passing through and secured against longitudinal movement in rack block 74 sliding in the groove formed in the bracket, to raise and lower the block on the bracket. A sector 76, meshing with rack 74, is secured to a rock-shaft 77 (Fig. 10) having a lever arm 78 (Fig. 1) adjustably secured by passing a pin through one of several holes to a link 80 connected to the link 54 which operates slide 52. The rocking of sector 76 by downward movement of the hold-down thus serves to move a roll carried by the bifurcated end of link 54 in a slot 82 in a lever 84, which is fulcrumed at 86 on a bracket attached to the machine frame and is connected to treadle 62 by means of a toggle 88, 90. By this arrangement movement of link 54 by link 80 varies the effective length of lever arm 84 so that completely straightening toggle 88, 90 moves slide 52 to bring the toe-embracing wipers exactly up to the desired predetermined position, here shown as being the position required for wiping inwardly over the shoe bottom. Further movement of treadle 62 in the same direction, during or

after the over-wiping operation, shortens the toggle and brings the wipers down on the wiped-over materials with a heavy ironing pressure.

5 In order to coordinate the position of the wipers with that of hold-down 60, the latter is adjustable on its supporting rod 64, being loosely mounted between flanges 94, 93 formed on a sleeve which is threaded on rod 10 64 and about which the hold-down may swing to and from position over a shoe in the machine. The sleeve is arranged to be turned by a handle 92 that is fast on the flange 96 to adjust the hold-down vertically 15 to coordinate its position with that of the wipers. The hold-down is held in adjusted vertical position by a suitable spring ratchet device 98, one part of which is carried by rod 64 and the other by flange 94, and which is 20 arranged to permit turning in either direction, while preventing the setting from being accidentally disturbed, and which locks the sleeve to rod 64.

For the double purpose of serving as a 25 counter-balance for the wiper-head in compressing the upper materials of a shoe against a last, and as a stop to assist the operator in determining when to move the wipers inwardly, a sliding rod 100 is yieldingly urged toward the left in Fig. 1 by a 30 spring 102 engaging a collar on the rod, as far as permitted by locknuts on the end of the rod (not shown), which engage the frame through which the rod slides. This 35 rod is so constructed and arranged that just as toggle 88, 90 is straightened, raising the wiper-head to its highest position, its head 104 is engaged by a set screw 106 in an arm 108 clamped on a rock-shaft 110 which carries treadle 62 (Figs. 1 and 10). In order 40 to insure the breaking of toggle 88, 90 on the reverse movement, the knuckle of the toggle is engaged by a spring pressed plunger 112.

45 By this arrangement, on the upward movement of the wiper head, while the wipers are held in engagement with the upper materials of the shoe in the usual manner, plunger 112 is pushed to the right, until engagement of set-screw 106 with head 104 50 notifies the operator to move the wipers inwardly over the shoe bottom. While treadle 62 may be held stationary during this motion of the wipers, this is not essential, as 55 the vertical motion of head 52 is comparatively slow while the toggle is just approaching and receding from its straightened position, a considerable arc of movement of member 90 at this time having a comparatively 60 small vertical component. During further manipulation of treadle 62, spring 102 is compressed and acts to counter-balance the weight of the wiper-head during 65 its downward motion in compressing the upper materials upon the shoe bottom. When

treadle 62 is released, spring 102 and plunger 112 co-operate in straightening toggle 88, 90 to return the wiper-head to its upper position, and plunger 112 acts to break the toggle in the opposite direction, whereupon the weight of the various parts, together with plunger 112 acting on the knuckle of toggle 88, 90, returns the parts to their initial positions.

70 It may be desirable in some cases to move the wiper-head to a substantially higher position in its reverse movement, in order to prevent possible loosening of the lasted upper materials by undue friction from the wipers as they are retracted. For this purpose, the secondary toggle shown in Fig. 2 75 may be substituted for member 90 shown in Fig. 1. This secondary toggle is made up of members 114, 116 which are pivoted together at 118. Member 114 is in two parts, the lower part terminating in an abutment face which is arranged to engage either of two angularly related faces 120, 122 on the bottom of member 116. Thus when the toggle rocks to the right to the position illustrated 80 in Fig. 2 during depression of treadle 62, the effective length of toggle 114, 116, and therefore of the compound toggle 114, 116, 88, is less than when it rocks back to the left with face 122 in engagement with the top face of 85 the bottom part of member 114, and with toggle 114, 116 accordingly straightened.

90 In order to insure that the return movement of toggle 114, 116 will always straighten it, member 116 carries a latch 124, in the form of a bell-crank lever, operated by a spring 126 and arranged to ride over and catch on a lug 130 on the frame of the machine. Just as face 122 engages member 114, the upper part of member 114 engages 95 a set-screw 128 carried by latch 124 and releases it. Thus latch 124 holds members 116 and 88 during the first part of the return movement, and when it is released the secondary toggle 114, 116 acts as a unit to form 100 a primary toggle with member 88. This compound toggle arrangement automatically provides for retracting the wipers at a higher level, and prevents any possible drag on the work.

110 It will be observed that adjustment of the wiper-head by handle 44, rocking it about spindle 42, changes the vertical position of the wipers and therefore disturbs the coordination of the wipers and hold-down 60. An important feature of my invention provides for convenient compensation for this 115 adjustment, preferably by means controlled by the adjustment itself. As illustrated, the spindle controlled by handle 44 is connected by means of a universal joint to a telescoping drive shaft 132, which is connected by a second universal joint to the threaded adjusting bolt 72. Thus manipulation of handle 44 to adjust the head about spindle 42 120 125 130

automatically raises or lowers rack block 74 to compensate for the movement of the wipers.

The wipers 140 (Figs. 8 and 13) are carried by carrier-plates 142, and are operated by a novel compensating mechanism which is to be described, and which is controlled by a manually-operated arm or lever 144, arranged to be locked by the usual eccentric 10 against a stationary arm 146 and to be released by a hand-grip 148.

The wiper-operating mechanism is supported on a wiper-carrier comprising a plate 150 (Figs. 1, 7 and 13) having a portion 152 secured thereto and to a carrier shaft 160, which slides in a sleeve 158 carried by or integral with the opposite arms of head 40. A front wiper-carrying portion 154 is also attached to the plate 150 in any suitable manner, and is secured to, or integral with, shaft 160. The wipers are adjusted about the axis of shaft 160 by manipulating a handle 162 to turn a threaded adjusting screw 164 mounted in an extension of head 40, thereby moving block 166 vertically. This block is connected by a pitman or link 168 with a spindle 170 slidably received in a recess in a lug on portion 154 of the wiper-carrier, and vertical motion of the block is transformed by these connections into angular motion of the wiper-carrier and wipers 140 about the axis of shaft 160.

The novel wiper-operating and compensating mechanism shown in Figs. 1, 7, 8, 35 12 and 13, is controlled, as stated above, by hand lever 144, which is pivoted at 180 on an arm 181 carried by sleeve 158 (Fig. 8 and 12), and which is connected by a link 182 (Fig. 8) with a pushrod 184 having a 40 guide portion sliding in a socket in shaft 160 (Fig. 13). The effect of longitudinal movement of the pushrod is controlled by a sleeve or sliding handle 186 on hand lever 144, which has three positions: (1) toward the operator, (2) central, and (3) toward the machine. The lever may, if desired, be provided with a spring-pressed pin 185 (Fig. 9) engaging three depressions on a member adjustably secured to rod 190 to determine the three positions.

Handle 186 carries a vertical extension 188 (Figs. 1, 8, and 9) to which is secured a rod 190 sliding in suitable guides 192 on hand lever 144. Rod 190 is connected at 191 to a lever 194 pivoted to an extension of arm 181 at 196 (Figs. 8 and 13), and connected by a sliding joint 197 to a vertical arm 198 secured to a rock-shaft consisting of two universal joints 202, a telescopic 60 central portion 204, a portion 206 carried by arm 181, and a portion 208 on the movable plate 150.

Portion 208 of this rock-shaft carries a vertical arm 210, connected by a link 212 with an arm 214 secured to a second rock

shaft 216 mounted in bearings in a cover-plate 218 secured to plate 150. Thus shafts 216 and 202-208 turn in opposite directions.

Motion of rod 184 is transmitted to a slide 220 moving in a slot in plate 150 (Figs. 7 and 13), which slide carries a pinion 222 meshing on one side with a rack 224 fastened to plate 150, and on the other side with a rack on a second or wiper-closing slide 226, formed with an upper ratchet surface as shown in Fig. 7. Slide 226 carries a pinion 228 meshing with racks on a third slide 230 and a fourth slide 232. Slide 230 carries a pawl 234 (Figs. 1 and 7), spring-pressed down against a ratchet member 243 connected to sleeve 158. A plunger 236 slides through a perforation in slide 230 to separate pawl 234 from the ratchet surface against the resistance of its spring.

As best shown in Fig. 14, ratchet member 243 is fastened by screws 245 to an upper part 235, which is secured by screws 241 to a lower part 237 to form a sleeve surrounding and rotatable on a reduced portion of sleeve 158 (Figs. 1, 12 and 13). Parts 235 and 237 are formed with co-operating lugs 239 for the reception of screws 241. At the right of Fig. 14, part 235 is formed with a machined surface slidably engaging a similar surface on the bottom of plate 150, and at the left in that figure ratchet member 243 is formed with a similar slidably-engaging machined surface. Thus the sleeve formed by parts 235 and 237 tilts about the axis of shaft 160 with the wiper-head, by reason of the sliding engagement at opposite sides with the bottom of plate 150, but is held from longitudinal motion by reason of its mounting on an annularly-reduced portion of the stationary sleeve 158.

Slide 232 (Figs. 7 and 13) carries a pinion 238 on its lower surface meshing with racks 239, which in turn drive pinions 240, 242 carried by part 154 of plate 150. The teeth of pinions 240, 242 are of such length vertically that they mesh with rack surfaces on the wiper-carriers 142, acting to open and close the wipers.

It has been noted that slide 230 is sometimes locked to head 40 through ratchet member 243, and can be released therefrom by depressing plunger 236. Slide 230 is of such shape, as shown in Fig. 7, that it has a limited movement with respect to plate 150, and when the limit of that movement is reached in either direction it may be regarded as locked to the plate. Rack 224 is at all times securely fastened to the plate 150. Slide 226 is arranged to be locked to plate 150 at times by pawl 246 carried by the cover 218 secured to the plate, which engages the ratchet surface on slide 226 through an opening in the cover.

Pinions 222 and 238 are secured on spindles which extend upwardly through

130

slots 248 and 250 in cover plate 218, and which carry segmental ratchet arms 252 and 254 (Fig. 8). Slides 220 and 232 respectively carry spaced lugs 256 and 258, between which are pivoted locking pawls 260 and 262 (Figs. 1, 8, and 13), normally spring-pressed upwardly, but which can be depressed against ratchet arms 252 and 254 to lock pinions 222 and 238 respectively to slides 220 and 232. Lugs 256 and 258, with their pawls, move in slots 264 and 266 in cover plate 218 as shown in Fig. 13 and in dotted lines in Fig. 8.

The locking and unlocking of the various parts is controlled by rock shaft 216 which is manipulated by sliding handle 186 back and forth. Shaft 216 carries an arm 268, in the end of which is a spring-pressed plunger 269 (Fig. 13) to engage and depress pawl 260, and there is also mounted on the shaft a sleeve 270 formed with a lug 272 (Figs. 8 and 12) to operate plunger 236 and an arm 274 which has an intermediate portion to engage the end of pawl 246, and which is formed with a head 275 carrying a spring-pressed plunger 273 to operate pawl 262.

Rocking the shaft 216 in one direction, by pulling handle 186 toward the operator to its first position, thus operates plunger 236 to release slide 230, allows pawl 246 to lock slide 226 to plate 150, and leaves pawls 260 and 262 in upper or idle position, thus releasing pinions 222 and 238. In this position movement of hand lever 144 forward 35 moves the whole wiper mechanism carried by plate 150 forward, for example to carry the wipers against the end face of the shoe, the wipers being free to turn together to the right or the left in fixed relation to each 40 other, to adjust themselves to the position of the toe by differential movement of slides 239, but being locked against closing by pawl 246.

Moving handle 186 to rock shaft 216 to its 45 intermediate or second position releases plunger 236, allowing pawl 234 to lock slide 230 to the head 40 through ratchet 243, and trips pawl 246 to release slide 226, but does not operate pawls 260 and 262, so that pinions 222 and 238 may turn. Now movement 50 of hand lever 144 operates slide 220, pinion 222 rolls on rack 224 to advance rack 226, pinion 228 rolls on the stationary rack 230 to advance rack 226, and therefore racks 239 turn pinions 240 and 242 to close the wipers. As 55 pinion 238 is at this time free, it acts as a compensating connection between the wipers, and as the pinion is moved bodily forward to close the wipers it will turn if the 60 resistance encountered by either of the wipers is greater than that encountered by the other, and thus substantially equalize the pressures of the wipers against the shoe 65 at the opposite sides of the toe. Moreover,

since the pinion 222 is free to turn and acts as a compensating connection between the wiper carrier and the closing slide 226, it serves at the same time to proportion the forward pressure of the wipers automatically to their closing pressure, and it may be substantially to equalize these pressures. That is, pinion 222 pushes on rack 224 to advance plate 150 (and with it the wipers) and at the same time the pinion 222 may roll 70 on rack 224 and pinion 228 on rack 230 to close the wipers. This results in a self-adjustment of the wipers to the shoe, however the contour of the shoe may vary, and is especially advantageous in the "upwipe", 80 since successive horizontal sections of a last and shoe at different levels may differ materially in outline. As the operator holds the wipers closed about the toe in the upwiping operation, they are thus at all times in the 85 most effective position relatively to the last and shoe, throughout this operation. This insures adequate wiping pressure at the sides of the toe as well as at the end of the toe.

Rocking shaft 216 by moving handle 186 toward the machine to its third position leaves rack 230 locked to the head, or stationary with respect to the relatively movable plate 150, and also leaves rack 226 free from pawl 246, but additionally operates to 95 lock pinions 222 and 238 by depressing pawls 260 and 262. Pinion 238 being thus locked, there is no differential or compensating relative movement of the wipers, which, however, are closed over the shoe bottom as slide 100 232 advances over plate 150. Locking the pinion 222 prevents movement of slide 226 relatively to plate 150, and thus eliminates the opportunity for self-adjustment or compensation as between the advance and the 105 closing of the wipers. Pinion 228 rolls on the relatively stationary rack 230, however, and thus advances rack 232 to close the wipers. This insures a definite relation between the closing and forward movements of 110 the wipers in a manner which retains, for the overwiping operation, the advantages of the manner of operation of machines of the type shown in the above-identified Letters Patent.

To secure the utmost benefit from the improved wiper operation, the wipers should be adjusted to the inclination of the shoe bottom with great exactness. To facilitate such adjustment, handle 44 is arranged to operate 120 an indicator, shown as a graduated drum 282 (Fig. 8), and handle 162 operates a similar indicator comprising a graduated drum 284. Each drum is in the form of a gear loosely mounted on the spindle operated by its associated handle and is driven therefrom by suitable reduction gearing 286 (Fig. 11).

In the illustrated embodiment of my invention, the holdown 60 is constructed and arranged to engage the sole at a plurality of 130

spaced points, and includes mechanism operated by such engagement to measure and indicate the transverse and longitudinal inclinations of the shoe bottom. The operation of this indicating mechanism is shown in Figs. 3-6 inclusive, and is effected by three shoe engaging plungers, one of which, indicated at 288, engages near the point of the toe, the others, 290 and 292, engaging at 10 opposite sides approximately in the vertical plane of the tip seam (Fig. 1).

As shown in Fig. 5, plungers 290 and 292 are pivoted on an equalizer bar 294, and slide through sleeves 296, which can be adjusted by a right-and-left-threaded screw 298 for shoes of different widths. Bar 294 is pivoted on a vertically movable slide 300, formed with a rack on one side of its upper end (Fig. 3), and carries a segmental rack 302 meshing with a pinion 304 fastened on the same spindle 306 as a second segmental rack 308, which meshes with a pinion 310 carried by the indicator drum 312. Pinion 310 and drum 312 are loosely mounted on 25 the spindle which connects bar 294 to slide 300, and so move vertically with the slide. The transverse inclination of the shoe bottom measured by this mechanism is read through an opening 314 in the casing of the 30 hold-down. A suitable pointer may be provided if desired.

The longitudinal inclination of the shoe bottom is determined by measuring the differential movement of plunger 288 and slide 35 300 (which may be regarded as controlled by a median point between plungers 290 and 292). The rack teeth on slide 300 engage a pinion 316, which meshes with teeth on plunger 288, permitting such a differential movement. As shown in Fig. 6, this movement is measured by the action of a 40 pinion 318 meshing with a second set of rack teeth on one side of plunger 288, this movement being transmitted through a large pinion 320 to a second small pinion 322 carried by measuring drum 324. The longitudinal inclination of the shoe is read on this 45 drum through an opening 326.

By this arrangement, when the hold-down 50 is brought against the bottom of a shoe in the machine, dials or drums 312 and 324 indicate exactly the transverse and longitudinal inclinations. By operating handles 44 and 162 to obtain corresponding readings 55 on indicators 282 and 284, accuracy of adjustment of the wipers to the shoe is insured. As all four of the indicators include means to multiply the motion which is measured, the readings are practically micrometer 60 readings, making possible an accuracy which could not be attained even by a skilled operator by eye measurements alone, and this accuracy is readily attainable by a relatively unskilled operator.

65 In operation, a last and shoe are jacked in

the machine in the usual way, the heel being lasted as with the present commercial machines. Hold-down 60 engages the bottom of the forepart of the shoe during the forepart lasting, the indicators facilitating quick 70 and exact adjustment of the wipers even before they are brought into engagement with the shoe. After the wipers have been adjusted to make them parallel to the shoe bottom, hand lever 144 is manipulated to 75 bring them up to the shoe. During this preliminary advance of the wipers, they have no closing movement, but are free to turn together to the right or left to adjust themselves to the position of the toe.

80 During the wiping of the upper materials upwardly against the sides of the last by manipulation of treadle 62, the wipers are held by the operator closed about the toe of the shoe by means of hand lever 144, and sliding handle 186 is at this time held in its middle position, in order to allow the wipers a compound compensating or differential motion, to equalize the pressure tending to move each wiper against the shoe and the 85 pressure urging them bodily forward against the toe of the shoe, thereby securing uniformity of pressure as between the sides and end of the toe. Thus the wipers remain throughout the upwiping operation in effective engagement with the upper materials all around the toe, regardless of variations in the contour of the last at different levels. The upper limit of this upward movement is automatically set by the hold-down, acting 90 through rack block 74.

95 Immediately following the upwiping operation, the upper materials are gathered and wiped inwardly over the shoe bottom by further manipulation of hand lever 144, the 100 wipers being locked against all differential or self-adjusting motion by shifting sliding handle 186 to its extreme position away from the operator on hand lever 144. This arrangement retains a great advantage of the 105 present commercial machine, in that the advancing and closing movements bear a predetermined definite relation to one another. There is, however, this additional advantage 110 that the wipers have previously automatically and exactly adjusted themselves to the contour of the shoe bottom during their upward wiping movement, and are thus set for the most effective action during their inward wiping movement. During the inward 115 movement of the wipers, the upper materials are compacted against the shoe bottom by further depression of treadle 62, this operation being facilitated by reason of the 120 fact that it is not necessary to reverse the 125 operation of the treadle. High quality work is rendered more certain by the impossibility of raising the wipers above the shoe bottom far enough to loosen the upper materials at the end of the upwiping operation, and 130

during the first part of the closing movement of the wipers, before they are pressed heavily toward the shoe bottom.

After the upper materials are secured in place, by tacking or wiring, as the case may be, the various parts are returned to their initial positions by releasing treadle 62, returning hand lever 144, and unjacking the shoe by operating the usual knee lever (not shown).

While one form of machine has been described in explaining my invention, it is not my intention to limit its scope thereby, or otherwise than by the terms of the appended claims. In various of its aspects it is applicable to lasting machines of other types, and in some aspects it is useful in connection with other operations than lasting.

Having described my invention, what I claim as new and desire to secure by Letters Patent of the United States is:—

1. A machine of the class described having, in combination, a shoe support, toe embracing wipers, operating mechanism for moving said wipers heightwise of the toe in wiping engagement with the upper materials, said operating mechanism comprising parts relatively adjustable to vary the limit of such movement of the wipers, and a device controlled by engagement with the shoe for effecting such relative adjustment in accordance with the location of the plane of the shoe bottom.

2. A machine of the class described having, in combination, a shoe support, toe embracing wipers, operating mechanism for moving said wipers heightwise of the toe in wiping engagement with the upper materials, said operating mechanism comprising a member having a constant limit of movement and a connection between said member and the wipers for transmitting movement from the member to the wipers, and a device controlled by engagement with the shoe for adjusting said connection to limit the movement of the wipers as determined by the shoe.

3. A machine of the class described having, in combination, a shoe support, toe embracing wipers, operating mechanism for moving said wipers heightwise of the toe in wiping engagement with the upper materials, said operating mechanism comprising a member connected to the wipers and having a constant limit of movement, and mechanism controlled by engagement with different shoes for determining different limits of movement of the wipers for the same limit of movement of said member.

4. A machine of the class described having, in combination, a shoe support, toe embracing wipers, operating mechanism for moving said wipers heightwise of the toe in wiping engagement with the upper materials, said operating mechanism comprising

a lever connected to the wipers and having a constant limit of movement, and mechanism controlled by engagement with the bottom of the shoe for varying the effective length of said lever to limit the movement of the wipers in accordance with the location of the plane of the shoe bottom.

5. A machine of the class described having, in combination, a shoe support, an end lasting mechanism, a lever for effecting relative movement of said support and lasting mechanism heightwise of the shoe, and means to vary the effective length of the lever to determine the extent of such relative movement to position the lasting mechanism in determinate relation to the shoe bottom.

6. A machine of the class described having, in combination, a shoe support, an end lasting mechanism, a lever for effecting relative movement of said support and lasting mechanism heightwise of the shoe, and means including a member engaging the shoe bottom to measure its height and to vary the effective length of the lever according to the measurement so made to determine the extent of such relative movement to position the lasting mechanism in determinate relation to the shoe bottom.

7. A machine of the class described having, in combination, a shoe support, toe embracing wipers, operating mechanism for moving said wipers heightwise of the toe in wiping engagement with the upper materials, said operating mechanism comprising a lever having a constant limit of movement and a link connecting said lever to the wipers and adjustable lengthwise of the lever, a member movable into engagement with the bottom face of the sole of the shoe, and connections between said member and link for adjusting the link by such movement of the member to determine the effective length of the lever in accordance with the location of the plane of the sole.

8. A machine of the class described having, in combination, a shoe support, lasting mechanism, a member having a movement of constant amplitude, a connection from said member for effecting relative movement of said support and lasting mechanism heightwise of the shoe, and means for adjusting said connection to vary the extent of such relative movement to position the lasting mechanism in determinate relation to the shoe bottom.

9. A machine of the class described having, in combination, a shoe support, lasting mechanism, a member having a movement of constant amplitude, a connection from said member for effecting relative movement of said support and lasting mechanism heightwise of the shoe, and means controlled by the shoe for adjusting said connection in accordance with the location of the plane of the shoe bottom to render effective more or

less of the movement of said member to position the lasting mechanism in determinate relation to said plane.

10. A machine of the class described having, in combination, a shoe support, an end lasting mechanism, and means relatively to move said support and lasting mechanism heightwise of the shoe, said means comprising two members pivoted together by a pin-and-slot connection for effecting said relative movement, means to impart a movement of predetermined amplitude to one of said members, and a device for adjusting said connection by moving the pin in the slot to vary the effective length of the one of the members and thereby to determine the extent of the relative movement to position the lasting mechanism in determinate relation to the shoe bottom.

20 11. A machine of the class described having, in combination, a shoe support, toe embracing wipers, treadle operated means for moving said wipers heightwise of the toe in wiping engagement with the upper materials comprising parts relatively adjustable to determine different limits of movement of the wipers for the same extent of movement of the treadle, and mechanism controlled by engagement with the shoe for effecting such relative adjustment of the parts in accordance with the requirements of the shoe.

12. A machine of the class described having, in combination, a work support and end embracing wipers relatively movable to wipe an upper heightwise of a form on said support and inwardly over the bottom of the form, operating mechanism for effecting such relative movement heightwise of the form comprising parts relatively adjustable to vary the limit of said movement, and mechanism controlled by the form for effecting such relative adjustment of the parts in accordance with the location of the plane of the bottom of the form.

15 13. A machine of the class described having, in combination, a shoe support, end embracing wipers, operating mechanism comprising a toggle and means for straightening it to effect relative movement of said shoe support and wipers heightwise of the shoe, and a device controlled by engagement with the bottom of the shoe for determining the position of the wipers relatively to the plane of the shoe bottom when the toggle is straight.

14. A machine of the class described having, in combination, a shoe support, lasting mechanism, a toggle for effecting relative movement of said support and lasting mechanism heightwise of the shoe, means for straightening the toggle for wiping the upper materials heightwise of the shoe and for breaking the toggle after the upper materials have been wiped inwardly over the edge of the shoe bottom to compress said

materials against the shoe bottom, and means controlled by engagement with the shoe for varying the amount of relative movement caused by straightening the toggle to co-ordinate the position of the shoe bottom and the position of the lasting mechanism when the toggle is straightened.

15. A machine of the class described having, in combination, a shoe support, toe embracing wipers, operating mechanism for moving said wipers heightwise of the toe in wiping engagement with the upper materials, said operating mechanism comprising a toggle connected to the wipers to position the wipers in predetermined relation to the plane of the shoe bottom when the toggle is straight, and means controlled by engagement with the bottom of the shoe for adjusting the connection between said toggle and the wipers to determine the position to which the wipers are moved by the straightening of the toggle.

16. A machine of the class described having, in combination, a shoe support, toe embracing wipers, operating mechanism for moving said wipers heightwise of the toe in wiping engagement with the upper materials, said operating mechanism comprising a toggle operated lever and a link connecting said lever to the wipers for positioning the wipers in predetermined relation to the plane of the shoe bottom when the toggle is straight, a hold-down movable into engagement with the bottom of the shoe, and connections between said hold-down and link for adjusting the link lengthwise of said lever to control in accordance with the location of the plane of the shoe bottom the movement which the wipers receive from the straightening of the toggle.

17. A machine of the class described having, in combination, a support for a shoe, a member adjacent thereto to operate on the side and bottom of a shoe supported thereby, connections including a lever relatively to move the support and said member in different directions successively to operate on the side and bottom of the shoe, respectively, and means to co-ordinate the position of the shoe and the position of said member at the time the direction of relative movement is changed, said means comprising a part engaging the shoe and a device controlled thereby to vary the effective length of said lever.

18. A machine of the class described having, in combination, a member movable in different directions to operate on the side and bottom of a shoe respectively, connections including a lever for operating said member, and means for co-ordinating the position of the shoe and the position of said member at the time its direction of movement is changed, said means comprising a member engaging the shoe and a device set

thereby and acting to vary the effective length of said lever.

19. A machine of the class described having, in combination, a member movable in different directions to operate on the side and bottom of a shoe respectively, connections for operating said member including an arm having a constant limit of movement, and means for co-ordinating the position of the shoe and the position of said member at the time its direction of movement is changed, said means comprising a part engaging the shoe and a device set thereby and acting to vary the extent of the movement imparted to said member by movement of the arm according to the position of the shoe.

20. A machine of the class described having, in combination, a last and shoe support, an end lasting mechanism including end-embracing wipers for wiping the upper heightwise of the last and over the bottom of the last, a toggle and a manually controlled member for straightening and breaking it, variable connections to transmit more or less of the movement of the toggle to the lasting mechanism to position it determinately with respect to the shoe bottom, and means to indicate to the operator when the toggle is straightened and the mechanism is in position for the overwiping operation.

21. A machine of the class described having, in combination, a last and shoe support, an end lasting mechanism including end-embracing wipers for wiping the upper heightwise of the last and over the bottom of the last, a toggle and a manually controlled member for straightening and breaking it, connections controlled by the shoe for transmitting more or less of the movement of the toggle to the lasting mechanism to position it determinately with respect to the shoe bottom, and a yielding device to indicate to the operator when the toggle is straightened and the mechanism is in position for the overwiping operation and to act as a counter-balance when the toggle is broken to lower the lasting mechanism to compress the upper against the bottom of the shoe.

22. A machine of the class described having, in combination, a shoe support, an end lasting mechanism for wiping the upper over the bottom of the shoe, a treadle and a connection therefrom for manually effecting variable relative movement of said support and lasting mechanism, and means controlled by the shoe for varying said connection to co-ordinate the position of the shoe and the position of the lasting mechanism prior to the over-wiping operation.

23. A machine of the class described having, in combination, a shoe support, an end lasting mechanism for wiping the upper over the bottom of the shoe, a treadle and an

arm rocked thereby, a link having a portion movably connected to said arm and operated by movement of the arm to effect relative movement heightwise of the shoe of said support and lasting mechanism, and means to move the link to vary the effective length of said arm to co-ordinate the position of the shoe bottom and the position of the lasting mechanism prior to the over-wiping operation.

24. A machine of the class described having, in combination, a shoe support, an end lasting mechanism for wiping the upper over the bottom of the shoe, a treadle and an arm rocked thereby, a link having a portion movably connected to said arm and operated by movement of the arm to effect relative movement of said support and lasting mechanism heightwise of the shoe, and means including a member to engage the shoe bottom to measure its height and a device controlled thereby to move the link to vary the effective length of said arm according to the measurement so made to co-ordinate the position of the shoe bottom and the position of the lasting mechanism prior to the over-wiping operation.

25. A machine of the class described having, in combination, a shoe support, lasting mechanism, a toggle for effecting relative movement of said support and lasting mechanism heightwise of the shoe, and means for straightening the toggle for wiping the upper materials heightwise of the shoe and for thereafter breaking the toggle to compress said materials against the shoe bottom.

26. A machine of the class described having, in combination, a shoe support, end embracing wipers, a manually operated controlling member, and operating mechanism for effecting in response to movement of said controlling member a relative movement of said shoe support and wipers to wipe the upper heightwise of the shoe and thereafter upon further movement of said member in the same direction a reverse relative movement to compress the margin of the upper on the bottom of the shoe.

27. A machine of the class described having, in combination, a shoe support, end embracing wipers, a treadle, and operating connections for effecting by movement of said treadle in one direction a relative movement of said shoe support and wipers to wipe the upper heightwise of the shoe and thereafter a reverse relative movement to compress the margin of the upper on the bottom of the shoe.

28. A machine of the class described having, in combination, a shoe support, toe embracing wipers movable heightwise of a shoe on said support, a toggle connected to said wipers, and a member movable to straighten the toggle for imparting unwiping movement to the wipers and operative by further movement in the same direction to break the

toggle for imparting reverse movement to the wipers to compress the margin of the upper on the shoe bottom.

29. A machine of the class described having, in combination, a shoe support, end embracing wipers, a treadle, connections between said treadle and the wipers operative through movement of the treadle in one direction to move the wipers heightwise of the shoe in wiping engagement with the upper and then to reverse their movement, and manually controlled means for closing the wipers over the bottom of the shoe when the treadle arrives at the point where the movement of the wipers is reversed.

30. A machine of the class described having, in combination, a shoe support, end embracing wipers, manually controlled means for closing said wipers about the end of the shoe and for thereafter advancing and closing them over the bottom of the shoe, and a treadle-operated toggle arranged to be straightened to move the wipers heightwise of the shoe to the overwiping plane and then to be broken by further movement of the treadle in the same direction to enable the operator to impart compressing movement to the wipers during or after their overwiping movement.

31. A machine of the class described having, in combination, a shoe support, end embracing wipers, means for closing said wipers about the end of the shoe and for thereafter advancing and closing them over the bottom of the shoe, a treadle, connections between said treadle and the wipers automatically operative in response to movement of the treadle in one direction to move the wipers heightwise of the shoe in wiping engagement with the upper materials and thereafter to reverse their movement for compressing the margin of the upper on the shoe bottom, and a device controlled by engagement with the bottom of the shoe for adjusting said wiper operating connections to determine in accordance with the location of the plane of the shoe bottom the point in the movement of the treadle when the movement of the wipers is reversed.

32. A machine of the class described having, in combination, a shoe support, end embracing wipers, manually controlled means for operating said wipers to close them about an end of the shoe and to wipe the margin of the upper inwardly over the bottom of the shoe, a manually operated member, connections between said member and the wipers automatically operative in response to movement of said member in one direction to effect relative movement of said shoe support and wipers heightwise of the shoe preparatory to the overwiping operation and thereafter to reverse said relative movement for compressing the margin of the upper on the bottom of the shoe, and a device for

signalling the operator at the point of reversal of said movement to indicate that the overwiping operation is to be performed.

33. A machine of the class described having, in combination, a shoe support, end embracing wipers, manually controlled means for operating said wipers to close them about an end of the shoe and to wipe the margin of the upper inwardly over the bottom of the shoe, a treadle, connections between said treadle and the wipers for effecting by movement of the treadle in one direction a wiping movement of the wipers heightwise of the shoe to the overwiping plane and thereafter a reverse movement of the wipers to compress the margin of the upper on the bottom of the shoe, and a device arranged to oppose yielding resistance to further movement of the treadle at that point in its movement where the movement of the wipers is reversed to signal the operator that the overwiping operation is to be performed.

34. A machine of the class described having, in combination, a shoe support, end embracing wipers, a toggle connected to said wipers for moving them heightwise of the shoe, an operating member for straightening said toggle to move the wipers to the overwiping plane and operative upon further movement in the same direction to break the toggle and reverse the movement of the wipers to compress the margin of the upper on the bottom of the shoe, and a device arranged to oppose yielding resistance to further movement of said operating member when the toggle is straight to indicate to the operator that the wipers are in the overwiping plane.

35. A machine of the class described having, in combination, a shoe support, an end lasting mechanism, means to co-ordinate the position of said mechanism and the position of the bottom of a shoe on the support, means to adjust said mechanism, and a connection from said adjusting means automatically to correct said co-ordinating means to compensate for the adjustment.

36. A machine of the class described having, in combination, a shoe support, an end lasting mechanism, means including a member to engage the shoe bottom to measure its height and a device controlled thereby to co-ordinate the position of said mechanism and the position of the bottom of the shoe, means to adjust said mechanism, and a connection from said adjusting means automatically to correct said co-ordinating means to compensate for the adjustment.

37. A machine of the class described having, in combination, a shoe support, end embracing wipers, means to co-ordinate the position of said wipers and the position of the bottom of a shoe on the support, means to tilt said wipers to make parallel the plane of operation thereof and the plane of the

shoe bottom, and a connection from said tilting means to correct the described co-ordination to compensate for said tilting.

38. A machine of the class described having, in combination, a shoe support, and end lasting mechanism, variable connections including a holddown device and a rack adjustably connected thereto to co-ordinate the position of the shoe bottom and the position of said mechanism, a hand-operated adjusting member to tilt said mechanism for alining it to operate on the shoe bottom, and an auxiliary connection from said adjusting member to adjust the position of said rack with respect to the holddown device to change the variable connections to compensate for the adjustment.

39. A machine of the class described having, in combination, a lasting instrumentality 20 to wipe up the side and inwardly over the bottom of a shoe, a feeler to determine the plane of the bottom of the shoe, means associated with the feeler for limiting with relation to that plane the extent of the upward wipe, a device for adjusting said instrumentality to aline it with respect to the shoe, and a connection associated with the adjusting device for correcting the operation of said limiting means according to the 30 adjustment.

40. A machine of the class described having, in combination, a device to operate on the side and bottom of a shoe, means for limiting the extent of operation on the side 35 of the shoe to position the shoe and said device determinately with respect to each other for operation on the bottom of the shoe, a manually-controlled member to adjust said device to aline it for operation on 40 the shoe bottom, and a connection from said member automatically to correct said limiting means according to the adjustment so made.

41. A machine of the class described having, in combination, a member to operate on 45 a shoe, means to determine the position of said member with respect to the shoe, means to adjust said member to aline it for operation on the shoe, and a connection from said 50 adjusting means to correct said positioning means according to the adjustment so made.

42. A machine of the class described having, in combination, a shoe support, end embracing wipers, operating means for effecting relative movement of said shoe support and wipers heightwise of the shoe comprising parts relatively adjustable to vary the limit of such movement mechanism controlled by engagement with the bottom of 60 the shoe for relatively adjusting said parts in accordance with the location of the plane of the shoe bottom, a device for adjusting said wipers relatively to the plane of the shoe bottom, and means for effecting by the 65 movement of said adjusting device a propor-

tional relative adjustment of said parts of the operating means to compensate for the adjustment of the wipers.

43. A machine of the class described having, in combination, a shoe support, toe embracing wipers, means for effecting relative movement of said shoe support and wipers to wipe the upper heightwise of the toe, means controlled by engagement with the bottom of the shoe for determining the limit of such relative movement, a device for adjusting said wipers relatively to the shoe, and means controlled by said adjusting device for further determining said limit of movement.

44. A machine of the class described having, in combination, a shoe support, toe embracing wipers, means for imparting to said wipers an automatically limited wiping movement heightwise of the toe, a device 55 for adjusting the wipers relatively to the plane of the shoe bottom, and mechanism controlled by said adjusting device for varying proportionally the limit of upwiping movement of the wipers.

45. A machine of the class described having, in combination, a shoe support, toe embracing wipers, operating means for imparting to said wipers a wiping movement heightwise of the toe comprising parts relatively adjustable to vary the limit of said movement, a device for adjusting the wipers relatively to the plane of the shoe bottom, and means for effecting by the movement of 95 said wiper adjusting device a proportional relative adjustment of said parts.

46. A machine of the class described having, in combination, a shoe support, toe embracing wipers, operating means for imparting to said wipers a wiping movement 105 heightwise of the toe comprising a lever connected to the wipers and having a constant limit of movement, mechanism controlled by engagement with the bottom of the shoe for varying the effective length of said lever in 110 accordance with the location of the plane of the shoe bottom, a device for adjusting the wipers relatively to said plane, and mechanism connected to said adjusting device for further varying the effective length of said lever to compensate for the adjustment of the wipers.

47. A hold-down for a machine of the class described comprising, in combination, 115 a threaded rod, a threaded sleeve mounted thereon and arranged to be turned manually to adjust it vertically on the rod, a hold-down member carried by the sleeve and freely rotatable thereon to turn to and from position over a shoe, and means for moving said rod to carry the hold-down member into engagement with the shoe.

48. A lasting machine comprising, in combination, lasting mechanism including wipers movable upwardly in engagement with 130

the upper about the end of a shoe and inwardly over the shoe bottom, and lever connections to move the wipers upwardly and to move them downwardly toward the shoe bottom to compress the upper materials of the shoe, said connections including means automatically to return the wipers on their reverse movement to a higher level than at the beginning of their downward movement to avoid loosening the shoe materials.

49. A lasting machine comprising, in combination, lasting mechanism including a member movable to wipe the upper materials of a shoe heightwise of the shoe and inwardly over the shoe bottom and reversely movable to withdraw it from the shoe, means to control relative movement of the shoe and said member to limit the upwipe and to position the member in determinate relation to the shoe bottom for the over wiping operation, and auxiliary means to modify the limiting action of said controlling means when the movement of the member is reversed to return said member at a higher level to prevent loosening frictional engagement with the upper materials.

50. In a machine of the class described, the combination with a wiping device and means for operating it to wipe the margin of an upper inwardly over the bottom of a form, of mechanism comprising a toggle for effecting relative movement between said wiping device and form to compress the margin of the upper on the bottom of the form, said mechanism including a secondary toggle automatically operative upon reverse movement of the mechanism to effect a greater separation between said wiping device and the plane of the bottom of the form than at the beginning of said compressing movement.

51. In a machine of the class described, the combination with wipers and means for operating them to wipe the margin of an upper inwardly over the bottom of a form about the end of the form, of a toggle arranged to be flexed to impart compressing movement to said wipers toward the bottom of the form and thereafter to be straightened to move the wipers reversely from the plane of the bottom of the form, and a device co-operating with said toggle to return the wipers to a position farther from the plane of the bottom of the form than at the beginning of their compressing movement.

52. In a machine of the class described, the combination with end embracing wipers and means for operating them to wipe the margin of an upper inwardly over the bottom of a form, of operating mechanism including a toggle for moving the wipers heightwise of the form to a position determined by the length of the toggle when straightened and thereafter by flexing of the

toggle to move the wipers toward the plane of the bottom of the form for compressing the margin of the upper, and a device automatically operative upon reverse movement of said mechanism to lengthen the toggle in its straightened condition for positioning the wipers farther from the plane of the bottom of the form than at the beginning of their compressing movement.

53. In a machine of the class described, the combination with toe embracing wipers and means for operating them to wipe the margin of an upper inwardly over the bottom of a last about the toe, of a treadle, connections between said treadle and the wipers operative by movement of the treadle in one direction to move the wipers heightwise of the toe and thereafter by further movement of the treadle in the same direction to move the wipers reversely toward the plane of the shoe bottom for compressing the margin of the upper, and a device automatically operative upon reverse movement of the treadle to cause the wipers to be returned to a position farther from the plane of the shoe bottom than at the beginning of their compressing movement.

54. In a machine of the class described, the combination with toe embracing wipers and means for operating them to wipe the margin of an upper inwardly over the bottom of a last about the toe, of a treadle, connections between said treadle and the wipers comprising a toggle arranged to be straightened to impart to the wipers a wiping movement heightwise of the toe and thereafter by further movement of the treadle in the same direction to be flexed for imparting to the wipers a compressing movement toward the plane of the shoe bottom, and a device automatically operative upon reverse movement of the treadle to lengthen said toggle in its straightened condition for moving the wipers to a position farther from the plane of the shoe bottom than at the beginning of their compressing movement.

55. A machine of the class described having, in combination, end-embracing wipers, means relatively to move said wipers and a form to upwipe the upper materials of the shoe against the sides of the form and to wipe them over the bottom of the form, means automatically to determine the level of the wipers as they move inwardly over the bottom of the form, and means to raise the wipers to a higher level when they are retracted.

56. In a machine for operating on shoes, the combination with a shoe support, of a measuring device mounted in position for engagement with a shoe on said support and having means for measuring and indicating by such engagement the inclination of a surface of the shoe which is to be operated upon.

57. In a machine for operating on shoes,

- the combination with a shoe support, of a measuring device comprising relatively movable members for engaging the bottom of the shoe respectively in different locations, and 5 an indicator operative in response to such relative movement of the members to show the inclination of the bottom of the shoe. 58. In a machine for operating on shoes, the combination with a shoe support, of a 10 measuring device movable into and out of position over the bottom of the shoe, said device comprising a plurality of relatively movable members for engaging the bottom of the shoe in locations spaced both lengthwise and laterally of the shoe, and indicators 15 operative in response to such relative movement of the members to show the inclinations of the bottom of the shoe both lengthwise and laterally of the shoe. 59. In a machine of the class described, the combination with shoe positioning means and a member for operating on the shoe, of a shoe engaging device having means for indicating by engagement with the shoe the 20 proper adjustment of said member relatively to the shoe, means for adjusting said member, and an indicating device associated with said member for correspondingly indicating when the member is properly adjusted. 60. In a machine of the class described, the combination with shoe positioning means and means for wiping the margin of the upper inwardly over the bottom of the shoe, of a device for engaging the bottom of the 25 shoe and for indicating by such engagement the inclination of the shoe bottom, means for angularly adjusting said wiping means relatively to the plane of the shoe bottom, and indicating mechanism operated by said adjustment of the wiping means to show when 30 said means is properly adjusted to the inclination of the shoe bottom. 61. In a machine of the class described, the combination with shoe positioning 45 means, and end-embracing wipers mounted for tipping movements both lengthwise and laterally of the shoe to adjust them to the shoe, of a measuring device comprising members for engaging the bottom of the shoe in 50 different locations, indicating means operated by relative movement of said members upon their engagement with the shoe to show the inclination of the bottom of the shoe both lengthwise and laterally of the shoe, and indicating mechanism operative in the 55 tipping movements of the wipers to show when they are adjusted in proper relation to the inclination of the bottom of the shoe. 62. In a machine of the class described, 60 the combination, with shoe positioning means and toe embracing wipers, of a measuring device arranged to engage the bottom of the shoe and having indicators to show respectively the inclinations of the shoe 65 bottom lengthwise and laterally of the shoe, adjusting devices arranged respectively to tip the wipers lengthwise and laterally of the shoe, and indicating devices associated with said adjusting devices to show when the wipers are properly adjusted to the inclinations of the shoe bottom. 63. A lasting machine comprising, in combination, lasting mechanism for laying the upper materials of a shoe over the shoe bottom, a device for measuring the inclination of the shoe bottom, and means to be adjusted according to the measured inclination to vary the inclination of said lasting mechanism to correspond to the inclination of the shoe bottom. 64. A lasting machine comprising, in combination, lasting mechanism for laying the upper materials of a shoe over a last, a device to engage the shoe and measure its angular position, and means to be adjusted according to the measured position to vary the angular adjustment of said lasting mechanism to correspond to the position of the shoe. 65. A lasting machine comprising in combination, lasting mechanism including wipers for wiping the upper materials of a shoe over the shoe bottom, a device to engage the shoe bottom and measure its transverse inclination, and means to be adjusted according to the measured inclination to vary the transverse inclination of said wipers to correspond to the inclination of the shoe bottom. 66. A lasting machine comprising, in combination, lasting mechanism including wipers for wiping the upper materials of a shoe over the shoe bottom, a device to engage the shoe bottom and measure its longitudinal inclination, and means to be adjusted according to the measured inclination to vary the longitudinal inclination of said wipers to correspond to the inclination of the shoe bottom. 67. A lasting machine comprising, in combination, mechanism for laying the upper materials of a shoe over the bottom of a form, means for measuring the transverse and longitudinal inclinations of the shoe bottom, and means to be adjusted according to the inclinations so determined to vary the transverse and longitudinal inclinations of said mechanism to correspond to the respective inclinations of the shoe bottom. 68. A lasting machine comprising, in combination, lasting mechanism including wipers and an angularly-adjustable mounting therefor to aline them with a shoe, a device for engaging spaced points on a shoe to measure its angular position, and means to adjust the angular position of said mounting according to the measurement so made to aline the wipers with the shoe. 69. A lasting machine comprising, in combination, lasting mechanism including wipers

and an angularly-adjustable mounting therefor to aline them with the bottom of a shoe, a device for engaging spaced points near the end and opposite sides of the bottom of the shoe to measure its transverse and longitudinal inclinations, and independent means to adjust said mounting according to the inclinations so measured to aline the wipers transversely and longitudinally with the shoe bottom.

70. A lasting machine comprising, in combination, lasting mechanism including wipers and an angularly-adjustable mounting therefor to aline them with the bottom of a shoe, connected members to be relatively moved into engagement with spaced points on the bottom of the shoe to measure by their relative movement the inclination of the bottom of the shoe, and means to adjust the angular position of the mounting according to the measurement so made to aline the wipers with the shoe.

71. A lasting machine comprising, in combination, lasting mechanism including wipers and an angularly-adjustable mounting therefor to aline them with a shoe, means to measure and indicate the angular position of the shoe, and means to adjust the mounting to change the angular position of the wipers accordingly.

72. A lasting machine comprising, in combination, lasting mechanism for operating on the bottom of a shoe, means to measure and indicate the inclination of the shoe bottom, and means to adjust said lasting mechanism to correspond to the inclination so indicated.

73. A lasting machine comprising, in combination, lasting mechanism including wipers and an angularly-adjustable mounting therefor to aline them with the bottom of a shoe, connected members to engage spaced points on a shoe and measure its angular position, an indicator to show the position measured thereby, and means to adjust said mounting to give the wipers a corresponding angular adjustment.

74. A lasting machine comprising, in combination, lasting mechanism including wipers and an angularly-adjustable mounting therefor to aline them with the bottom of a shoe, connected members to engage spaced points near the end and opposite sides of the bottom of a shoe and measure its transverse and longitudinal inclinations, indicating means to show the inclinations measured thereby, and means to adjust the mounting to give the wipers corresponding transverse and longitudinal inclinations.

75. A machine of the class described having, in combination, means to operate on the bottom of a shoe, means to engage the shoe bottom and measure its inclination, and means to tilt said operating means to co-

ordinate its position with that of the shoe bottom.

76. A machine of the class described having, in combination, means to operate on the bottom of a shoe, members to engage points adjacent the end and opposite sides of the shoe bottom and measure its transverse and longitudinal inclinations, and means to tilt said operating means transversely and longitudinally to co-ordinate its position with that of the shoe bottom.

77. A machine of the class described having, in combination, means to operate on the bottom of a shoe, means to engage the shoe bottom and measure its inclination, an indicator operated by such engagement to show the measurement so made, and means to tilt said operating means to co-ordinate its position with that shown on the indicator.

78. A machine of the class described having, in combination, means to operate on a shoe, means to engage the shoe bottom and measure its position, and means to adjust the operating means according to the measurement so made.

79. A machine of the class described having, in combination, means to operate on a shoe, members to engage spaced portions of a shoe to measure its angular position, an indicator to show the measurement determined thereby, and means to adjust the angular position of the operating means according to the measurement so indicated.

80. A lasting machine comprising, in combination, lasting mechanism including wipers and an angularly-adjustable mounting therefor, means for adjusting the mounting, and an indicator controlled by operation of the adjusting means to show the angular position of the wipers.

81. A lasting machine comprising, in combination, end embracing wipers, means for tilting the wipers to adjust them relatively to the bottom of a shoe, and an indicator controlled by the tilting of the wipers to show when they are in the desired relation to the shoe bottom.

82. A lasting machine comprising, in combination, lasting mechanism including wipers and an angularly-adjustable mounting therefor, independent devices for tilting the mounting transversely and longitudinally, and indicators controlled by operation of the tilting means to show the transverse and longitudinal inclinations of the wipers.

83. A lasting machine comprising, in combination, lasting mechanism including wipers and an angularly-adjustable mounting therefor, hand-operated gearing for adjusting the mounting, and an indicator driven by said gearing to show the angular position of the wipers.

84. A lasting machine comprising, in combination, lasting mechanism including wipers

and an angularly-adjustable mounting therefor, a device including a rotatable member to adjust the mounting, and an indicator drum and reduction gearing connecting it to said member to provide an accurate measurement of the angular position of the wipers.

85. A hold-down for a lasting machine having means to measure and indicate the inclination of the bottom of a shoe.

86. A hold-down for a lasting machine having a plurality of connected members to engage spaced points on the bottom of a shoe, and means operated by relative movement of said members to indicate the inclination of the shoe bottom.

87. A hold-down for a lasting machine having a plurality of connected members to engage spaced points adjacent the end and opposite sides of the bottom of a shoe, and means operated by relative movement of said members to indicate the transverse and longitudinal inclinations of the shoe bottom.

88. A hold-down for a lasting machine having a plurality of connected members to engage spaced points on the bottom of a shoe, and a gear-driven indicator drum operated by relative movement of said members to indicate the inclination of the shoe bottom.

89. A device for measuring the inclination of the bottom of a shoe comprising, in combination, means to engage spaced points on the bottom of the shoe, and a scale and index relatively moved by movement of said means to show the inclination of the shoe bottom.

90. A device for measuring the inclination of the bottom of a shoe comprising, in combination, members to engage the bottom of the shoe in different locations, a connector tilted by relative movement of said members, and means operated by the tilting of said connector to show the inclination of the shoe bottom.

91. In a machine of the class described, the combination with shoe positioning means, of end embracing wipers, means for advancing said wipers bodily toward the end of the shoe, wiper closing mechanism operative in response to movement of said advancing means, and means for locking said wiper closing mechanism to prevent relative closing movement of the wipers as they are advanced toward the end of the shoe and for subsequently unlocking said mechanism to permit the closing of the wipers.

92. In a machine of the class described, the combination with shoe positioning means, of end embracing wipers, a wiper carrier, means for moving said wiper carrier to advance the wipers toward the end of the shoe, a member mounted on said wiper carrier and movable relatively to said carrier in response to movement of said advancing means to close the wipers about the end of the shoe, and means

for locking said member to the wiper carrier to prevent closing movement of the wipers until they have been advanced toward the shoe.

93. In a machine of the class described, the combination with shoe positioning means, of end embracing wipers, a wiper carrier, a member movably mounted on said wiper carrier for closing the wipers about the end of the shoe, an operating member, a compensating connection between said operating member and the wiper carrier and the closing member for both advancing the carrier and closing the wipers with forward and closing pressures automatically proportioned by resistance of the shoe, and means for holding said wiper closing member from movement relatively to the wiper carrier to prevent closing of the wipers as they are advanced toward the end of the shoe.

94. In a machine of the class described, the combination with shoe positioning means, of end embracing wipers, a wiper carrier, a wiper closing slide connected to the wipers and movably mounted on said carrier, a bodily movable pinion affording a compensating connection between said closing slide and the wiper carrier, means operating through said pinion to advance the wiper carrier and close the wipers, and means for locking said slide from movement relatively to the wiper carrier to cause the wipers to be advanced toward the end of the shoe without closing movement and for subsequently unlocking it to permit the closing of the wipers.

95. In a machine of the class described, the combination with shoe positioning means, of end embracing wipers, a wiper carrier, an operating member movable relatively to said wiper carrier and having a pinion mounted thereon, a rack fast on the wiper carrier and engaging said pinion, a wiper closing member movably mounted on the wiper carrier and having rack teeth also engaging said pinion, and means for locking said wiper closing member from movement relatively to the wiper carrier to render the pinion effective to advance the wiper carrier and wipers without closing movement of the wipers and for subsequently unlocking said member to permit it to be operated by turning movement of the pinion to close the wipers.

96. In a machine of the class described, the combination with shoe positioning means, of end embracing wipers, a wiper carrier, a wiper closing member movably mounted on said wiper carrier, a hand lever, a compensating connection between said hand lever and the wiper carrier and the wiper closing member for advancing said carrier and the wipers and for closing the wipers about the end of the shoe by the operation of said lever with forward and

- closing pressures automatically proportioned by resistance of the shoe, a device for locking said closing member from movement relatively to the wiper carrier 5 to prevent closing of the wipers as they are advanced, and means on said hand lever for controlling said locking device to unlock the wiper closing member.
97. In a machine of the class described, 10 the combination with shoe positioning means, of end embracing wipers, a member for advancing said wipers toward the end of the shoe, wiper closing connections arranged to be operated by said member to close the 15 wipers about the end of the shoe, and means for locking said wiper closing connections to prevent the closing of the wipers by said member as the wipers are advanced.
98. A lasting machine comprising, in combination, shoe-engaging wipers, a carrier therefor, a movable operating arm, and connections from the arm arranged to be set at the will of the operator to advance the carrier any distance between its limits of movement without closing the wipers or to close 25 the wipers.
99. In a machine of the class described, the combination with shoe positioning means, of end embracing wipers, means for advancing said wipers toward the end of the shoe without relative closing movement, and connections between the wipers constructed to permit them to shift bodily to the right or the left upon engagement with the shoe 35 while they are held from relative closing movement.
100. In a machine of the class described, the combination with shoe positioning means, of end embracing wipers, and a rack 40 and pinion connection between said wipers constructed to permit them to shift bodily to the right or the left upon engagement with the shoe while maintaining them in the same relation to each other.
101. In a machine of the class described, the combination with shoe positioning means, of end embracing wipers, pinions connected to said wipers for closing them, racks engaging said pinions, and a pinion affording a connection between said racks to 50 permit the wipers to shift in one direction or the other without relative movement between them.
102. In a machine of the class described, the combination with shoe positioning means, of end embracing wipers, connections between said wipers constructed to permit them to shift to the right or the left upon engagement with the shoe while maintaining them in the same relation to each other, and means for subsequently operating said connections to close the wipers about the end of the shoe.
103. In a machine of the class described, 60 the combination with shoe positioning means, of end embracing wipers, rack and pinion connections between said wipers including a pinion common to both wipers to permit them to shift to the right or the left upon engagement with the shoe without relative movement between them, and means for subsequently imparting bodily movement to said pinion to close the wipers about the end of the shoe.
104. A lasting machine comprising, in combination, lasting mechanism including end-embracing wipers and a carrier therefor, connections for advancing the carrier and closing the wipers, and means for controlling said connections (1) to advance the 65 carrier while permitting the wipers to turn to the right or the left without relative closing movement, (2) to close the wipers about the end of the shoe while pressing them forwardly with automatic compensation between their forward pressure and their closing pressure, and (3) to advance and close the wipers proportionately over the bottom of the shoe without such compensation.
105. A lasting machine comprising, in combination, lasting mechanism including end-embracing wipers and a carrier therefor, connections for advancing the carrier and closing the wipers, means relatively to move a shoe and the wipers to wipe the upper materials heightwise of the shoe, and means for controlling said connections (1) to advance the carrier and the wipers without closing movement of the wipers, (2) to close the wipers and to hold them closed about the end 75 of the shoe with automatic compensation between their forward pressure and their closing pressure during the upwiping operation, and (3) finally to advance and close the wipers proportionately over the bottom of the shoe without such compensation.
106. A lasting machine comprising, in combination, end-embracing wipers, a rack and pinion associated with each wiper to open and close it, a pinion connecting the 80 racks, and means to lock and unlock the connecting pinion.
107. In a machine of the class described, the combination with shoe positioning means, of end embracing wipers, pinions connected to said wipers for closing them, racks connected to said pinions, a pinion affording a connection between said racks, and means for imparting bodily movement to said last named pinion to operate the racks for closing the wipers while permitting said pinion to turn to afford a compensating connection between the different wipers.
108. In a machine of the class described, the combination with shoe positioning means, of end embracing wipers, pinions connected to said wipers for closing them, racks connected to said pinions, a pinion affording a connection between said racks, means for advancing the wipers and for imparting bodily 85 movement to said pinion to close the wipers about the end of the shoe.

movement to said last named pinion to close the wipers about the end of the shoe, and means for preventing bodily movement of said last named pinion relatively to the 5 wipers as the wipers are advanced toward the shoe to prevent closing of the wipers while leaving said pinion free to turn to permit the wipers to adjust themselves to the position of the shoe.

10 109. A lasting machine comprising, in combination, means to wipe the upper materials of a shoe heightwise of a last and over a sole on the last bottom, and connections to operate said means constructed and arranged 15 to permit automatic adjustment thereof the sides of the last as the successive sections of the last vary in contour, and to lock said means to preserve the adjustment so made as the shoe bottom is reached and to 20 cause an unyielding predetermined change from such adjusted position in wiping inwardly over the shoe bottom.

110. A lasting machine comprising, in combination, lasting mechanism including 25 end-embracing wipers, means relatively to move the wipers and a shoe and last in a direction substantially perpendicular to the shoe bottom to wipe the upper materials of the shoe upwardly against the sides of the 30 last, and means to advance and retract and to open and close the wipers, including connections arranged to be set manually to cause the wipers to adjust themselves to the shoe 35 with substantially equal pressures against the end and the sides of the shoe during the upwiping operation and thereafter to lock them against such adjustment to wipe the upper materials over the shoe bottom.

111. A lasting machine comprising, in 40 combination, lasting mechanism including end-embracing wipers, a device for operating the wipers, and connections controlled by said device alternately (1) to open and close the wipers and advance and retract them in 45 fixed proportion to the movement of said device, or (2) to advance and close the wipers with automatic compensation between their advancing pressure and their closing pressure.

50 112. A lasting machine comprising, in combination, lasting mechanism including end-embracing wipers, a gear connection between the wipers to allow them differentially to adjust themselves to a shoe, means to lock 55 the connection when the wipers are so adjusted, and means to open and close the wipers whether or not the connection is locked.

113. In a machine of the class described, 60 the combination with shoe positioning means, of end embracing wipers, mechanism for closing said wipers about the end of the shoe including a compensating connection between the wipers to permit them to move 65 relatively to each other in response to re-

sistance of the shoe to conform to the contour of the shoe, and means for locking said compensating connection to prevent the compensating action as the wipers are closed inwardly over the bottom of the shoe.

70 114. In a machine of the class described, the combination with shoe positioning means, of end embracing wipers, rack and pinion mechanism for closing said wipers about the end of the shoe including a pinion mounted 75 for bodily movement to close the wipers and for turning movement to permit a compensating relative adjustment of the wipers to the shoe, and means for locking said pinion from turning movement to prevent 80 said compensation as the wipers are closed inwardly over the bottom of the shoe.

115. In a machine of the class described, 85 the combination with shoe positioning means, of end embracing wipers, a wiper carrier for advancing said wipers toward the end of the shoe, a member movable relatively to the wiper carrier for closing the wipers about the end of the shoe, means for advancing 90 said wiper carrier and for operating said closing member including a compensating connection between said member and the carrier for substantially equalizing the closing pressure and the advancing pressure of the wipers, means for subsequently locking said 95 closing member from movement relatively to the carrier, and mechanism operative when said member is thus locked to cause a closing movement of the wipers in fixed proportion to their advancing movement for 100 wiping the upper over the bottom of the shoe.

116. In a machine of the class described, 105 the combination with shoe positioning means, of end embracing wipers, a wiper carrier for advancing said wipers toward the end of the shoe, a wiper closing member movable relatively to said wiper carrier and having a pinion mounted thereon for closing the wipers about the end of the shoe, means for 110 advancing said carrier and for operating said closing member including a compensating connection between said member and carrier for substantially equalizing the advancing and closing pressures of the wipers, means for locking said closing member to the wiper carrier after the wipers have been closed about the end of the shoe, and a rack 115 engaging said pinion and relatively to which the wiper carrier is moved when said member is locked to impart to the wipers closing movement in fixed proportion to their advancing movement.

117. In a machine of the class described, 120 the combination with shoe positioning means, of end embracing wipers, a wiper carrier, a slide on said wiper carrier having a pinion mounted thereon, a rack fixed on the wiper carrier and engaging said pinion, a second 125 slide movably mounted on the wiper carrier 130

and having rack teeth engaging said pinion, a pinion mounted on said second slide, a rack arranged to be held stationary relatively to the wiper carrier and engaging said last named pinion, and a third slide on the wiper carrier having rack teeth engaging said last named pinion, said third slide being connected to the wipers to close them by the operation of said racks and pinions.

118. In a machine of the class described, the combination with shoe positioning means, of end embracing wipers, means for effecting relative movement of said shoe positioning means and wipers to wipe the upper heightwise of the shoe, means for advancing and closing the wipers about the end of the shoe and for holding them closed during the upwiping operation including compensating means for substantially equalizing the pressures of the wipers as between the end and the sides of the shoe, and additional means for subsequently causing the wipers to advance and close inwardly over the bottom of the shoe without such compensation.

119. In a machine of the class described, the combination with shoe positioning means, of end embracing wipers, means for effecting relative movement of said shoe positioning means and wipers to wipe the upper heightwise of the shoe, means for advancing and closing the wipers about the end of the shoe and for holding them closed during the upwiping operation including compensating means for substantially equalizing the pressures of the wipers as between the end and the sides of the shoe, means for locking said compensating connections against compensating movement at the end of the upwiping operation, and additional means for thereafter advancing the wipers over the bottom of the shoe and for effecting a closing movement of the wipers in fixed proportion to their advancing movement.

120. In a machine of the class described, the combination with shoe positioning means, of end embracing wipers, a hand lever, mechanism operated by said hand lever for advancing and closing the wipers about the end of the shoe and inwardly over the bottom of the shoe including a compensating device for automatically proportioning the advancing and closing pressures of the wipers in response to the resistance encountered by the wipers, and a device associated with said hand lever for preventing such compensation and for setting said mechanism to insure a fixed relation between the advancing movement of the wipers and their closing movement.

121. In a machine of the class described, the combination with shoe positioning means, of end embracing wipers, an operating member, mechanism operated by said member for both advancing the wipers lengthwise of the shoe and for closing them laterally of the

shoe, said mechanism including a compensating connection automatically operative in response to resistance of the shoe to proportion the advancing pressure of the wipers to the closing pressure as the wipers are closed about the end of the shoe, and a device for rendering said compensating connection inoperative thereby to prevent the compensating action as the wipers are closed inwardly over the bottom of the shoe.

122. In a machine of the class described, the combination with shoe positioning means, of end embracing wipers, a wiper carrier, a wiper closing member connected to the wipers and movably mounted on said carrier, and mechanism for advancing said carrier and for operating said closing member including a pinion affording a compensating connection between said carrier and member to proportion the forward pressure of the wipers automatically to their closing pressure in response to resistance of the shoe, and means for locking said pinion from turning movement to prevent the compensating action as the wipers are closed inwardly over the bottom of the shoe.

123. In a machine of the class described, the combination with shoe positioning means, of end embracing wipers, operating means for advancing said wipers toward the end of the shoe and for closing them laterally of the shoe, said operating means including compensating connections automatically responsive to resistance of the shoe substantially to equalize the advancing pressure and the closing pressure of the wipers and also to equalize the closing pressures of the wipers at the opposite sides of the shoe, and means for subsequently preventing said compensating action as the wipers are advanced and closed over the bottom of the shoe.

124. In a machine of the class described, the combination with shoe positioning means, of end embracing wipers, a wiper carrier, a member movably mounted on said wiper carrier for closing the wipers, rack and pinion mechanism between said member and the wipers including a pinion movable bodily to close the wipers and operative by turning movement as a compensating member substantially to equalize the pressures of the wipers against the opposite sides of the shoe, means for advancing said wiper carrier and for operating said closing member including a pinion affording a compensating connection between said carrier and member for proportioning the advancing pressure of the wipers to their closing pressure in response to resistance of the shoe, and means for locking said pinions after the wipers have been closed about the end of the shoe to prevent their compensating action as the wipers are advanced and closed over the bottom of the shoe.

125. In a machine of the class described, the combination with shoe positioning means, of end embracing wipers, means for effecting relative movement of said shoe positioning means and wipers to wipe the upper heightwise of the shoe, means for advancing and closing the wipers about the end of the shoe and for holding them closed during the upwiping operation including compensating devices automatically operative in response to resistance of the shoe substantially to equalize the advancing pressure and the closing pressure of the wipers and also to equalize the closing pressures of the wipers at the opposite sides of the shoe, and mechanism for locking said compensating devices after the upwiping operation to prevent their compensating action during the overwiping operation. 75
126. In a machine of the class described, the combination with shoe positioning means, of end embracing wipers, means for effecting relative movement of said shoe positioning means and wipers to wipe the upper heightwise of the shoe, and manual means for closing said wipers about the end of the shoe and for holding them closed during the upwiping operation including parts relatively movable in response to differences in the resistance encountered by the wipers as between the end and the sides of the shoe to cause the wipers to maintain effective engagement with the upper at the end and sides of the shoe throughout the upwiping operation. 80
127. In a machine of the class described, the combination with shoe positioning means, of end embracing wipers, means for effecting relative movement of said shoe positioning means and wipers to wipe the upper heightwise of the shoe, and manually operated means for advancing and closing the wipers about the end of the shoe and for holding them closed during the upwiping operation including a compensating connection automatically operative through engagement of the wipers with the shoe substantially to equalize the pressures of the wipers as between the end and the sides of the shoe. 85
128. In a machine of the class described, the combination with shoe positioning means, of end embracing wipers, an operating member, and positive connections between said member and the wipers for advancing them and for closing them about the end of the shoe including a compensating device for substantially equalizing the advancing and closing pressures of the wipers in response to the resistance of the shoe materials. 90
129. In a machine of the class described, the combination with shoe positioning means, of end embracing wipers, a wiper carrier, a wiper closing member movably mounted on said wiper carrier and positively connected to the wipers, a hand lever, and positive connections between said hand lever and the wiper carrier and closing member for advancing and closing the wipers including a compensating device automatically operative in response to resistance of the shoe materials substantially to equalize the pressures of the wipers as between the end and the sides of the shoe. 95
130. In a machine of the class described, the combination with shoe positioning means, of end embracing wipers, a wiper carrier, a member movably mounted on said wiper carrier for closing the wipers about the end of the shoe, an operating member for both advancing the wiper carrier and for operating said closing member, and a compensating connection between the wiper carrier and the closing member automatically operative in response to resistance of the shoe substantially to equalize the advancing and closing pressures of the wipers against the shoe. 100
131. In a machine of the class described, the combination with shoe positioning means, of end embracing wipers, an operating member, and mechanism operated by said member for both advancing the wipers lengthwise of the shoe and for closing them laterally of the shoe, said mechanism including a compensating connection automatically operative in response to resistance of the shoe substantially to equalize the advancing pressure of the wipers and the closing pressure. 105
132. In a machine of the class described, the combination with shoe positioning means, of end embracing wipers, a wiper carrier, a wiper closing slide connected to the wipers and movably mounted on said carrier, and mechanism for advancing said carrier and for operating said closing slide including a pinion affording a compensating connection between said carrier and slide to proportion the forward pressure of the wipers automatically to their closing pressure in response to resistance of the shoe. 110
133. In a machine of the class described, the combination with shoe positioning means, of end embracing wipers, and means for closing said wipers about the end of the shoe including a rack and pinion connection between the different wipers having a compensating action in response to resistance of the shoe for substantially equalizing pressures of the wipers against the opposite sides of the shoe. 115
134. In a machine of the class described, the combination with shoe positioning means, of end embracing wipers, and operating means for advancing said wipers toward the end of the shoe and for closing them laterally of the shoe, said operating means including a compensating connection 120
135. In a machine of the class described, the combination with shoe positioning means, of end embracing wipers, and operating means for advancing said wipers toward the end of the shoe and for closing them laterally of the shoe, said operating means including a compensating connection 125

automatically operative in response to resistance of the shoe to proportion the advancing pressure of the wipers to the closing pressure and also a compensating connection between the different wipers for substantially equalizing their pressures at the opposite sides of the shoe in response to resistance of the shoe.

135. In a machine of the class described, 10 the combination with shoe positioning means, of end embracing wipers, a wiper carrier, a member movably mounted on said carrier for closing the wipers, mechanism connecting said member to the wipers including a compensating connection responsive to resistance of the shoe substantially to equalize the pressures of the wipers at the opposite sides of the shoe, and means for advancing said wiper carrier and for 20 operating said closing member including a compensating connection between said carrier and member for automatically proportioning the advancing pressure and the closing pressure of the wipers in response to 25 resistance of the shoe.

136. In a machine of the class described, the combination with shoe positioning means, of end embracing wipers, a wiper carrier, a member movably mounted on said 30 wiper carrier for closing the wipers, rack and pinion mechanism between said member and the wipers including a pinion affording a compensating connection between the wipers for substantially equalizing their pressures 35 against the sides of the shoe, and means for advancing said wiper carrier and for operating said closing member including a pinion affording a compensating connection between said carrier and member for automatically proportioning the advancing pressure 40 of the wipers to their closing pressures.

137. In a machine of the class described, the combination with shoe positioning means, of end embracing wipers, means for 45 effecting relative movement of said shoe positioning means and wipers to wipe the upper heightwise of the shoe, and means for advancing and closing the wipers about the end of the shoe and for holding them closed 50 during the upwiping operation including compensating mechanism for substantially equalizing the pressures of the wipers as between the end and the sides of the shoe and for also substantially equalizing the 55 pressures of the wipers as between the opposite sides of the shoe.

138. A lasting machine comprising, in combination, lasting means including end-embracing wipers and connecting differential gearing, and means for opening and closing the wipers through said gearing including additional differential gearing to afford automatic compensation between the advancing pressure of the wipers and their 65 closing pressure.

139. A lasting machine comprising, in combination, means including end-embracing wipers for forming the upper of a shoe to its last, means for relatively moving the shoe and wipers to upwipe the upper, means for advancing and closing the wipers including a compensating connection for substantially equalizing the advancing and the closing pressures of the wipers, and a single manually-controlled device for operating 70 said last-named means and for rendering said compensating connection either operative or inoperative.

140. A bed lasting machine having, in combination, a last and shoe support, lasting mechanism including end-embracing wipers, manual means for relatively moving said mechanism and the last to upwipe the shoe materials, a manually-movable arm to open and close and to advance and retract the wipers, and connections from the arm to the wipers including differentially-movable self-adjusting means to allow the wipers to vary their position during the upwipe to conform to the different contours of the last 80 and shoe at different levels.

141. A bed lasting machine having, in combination, a last and shoe support, lasting mechanism including end-embracing wipers, means to move said mechanism to upwipe the shoe materials, a manually-movable arm to open and close and to advance and retract the wipers, connections from the arm to the wipers including differentially-movable self-adjusting means to allow the wipers to vary 90 their position during the upwipe to conform to the different contours of the last and shoe at different levels, and a locking device associated with said arm for locking the differential means at the end of the upwipe to cause a predetermined advancing and closing movement of the wipers from their position at that time proportionate to the movement of said arm.

142. A lasting machine comprising, in combination, end-embracing wipers, a movable carrier to advance and retract the wipers, a slide movable relatively to said carrier for opening and closing the wipers, the carrier and slide each being provided with a rack surface, a pinion meshing with the racks, and means to move the pinion bodily while permitting it to turn to advance the carrier and the slide.

143. A lasting machine comprising, in combination, end-embracing wipers, a movable carrier to advance and retract the wipers, a slide movable relatively to said carrier for opening and closing the wipers, the carrier and slide each being provided with a rack surface, a pinion meshing with the racks, means to move the pinion bodily while permitting it to turn to advance the carrier and the slide, and means to lock said pinion from turning movement.

144. A lasting machine comprising, in combination, end-embracing wipers, an arm and variable connections therefrom to operate the wipers, mechanism to vary the connections to change the action of the wipers, and a sliding handle mounted on the arm and means operated by sliding the handle on the arm for operating said mechanism.

145. A lasting machine comprising, in combination, a support, a carrier movable on

the support, wipers mounted in the carrier for closing movement therein, a rack locked to the support, a pinion rolling on the rack and connected to the carrier, and connections from the pinion to close both wipers ¹⁵ through an angle proportionate to the extent of movement of the carrier.

In testimony whereof I have signed my name to this specification.

ARTHUR F. PYM.

Certificate of Correction.

Patent No. 1,634,510.

Granted July 5, 1927, to

ARTHUR F. PYM.

It is hereby certified that error appears in the printed specification of the above-numbered patent requiring correction as follows: Page 8, line 84, claim 6, for the syllable "rela-" read *relative*; page 18, line 43, claim 111, for the word "alternately" read *alternatively*; and that the said Letters Patent should be read with these corrections therein that the same may conform to the record of the case in the Patent Office.

Signed and sealed this 8th day of November, A. D. 1927.

[SEAL.]

M. J. MOORE,
Acting Commissioner of Patents.
